UNITED STATES PATENT OFFICE.

GASTON J. GORY, OF CHICAGO, ILLINOIS.

PARCEL-WRAPPER.

1,293,085.

Specification of Letters Patent.

Patented Feb. 4, 1919.

Application filed November 17, 1915. Serial No. 61,888.

To all whom it may concern:

Be it known that I, GASTON J. GORY, a citizen of the United States, and a resident of the city of Chicago, county of Cook, and 5 State of Illinois, have invented certain new and useful Improvements in Parcel-Wrap-
pers, of which the following is a specifica-
tion.

My invention relates to improvements in 10 parcel wrappers and has for its object the provision of an improved construction of this character which is capable of economical manufacture and efficient in use.

The invention consists in the combinations 15 and arrangements of parts hereinafter described and claimed.

The invention will be best understood by reference to the accompanying drawings, forming a part of this specification, and in 20 which—

Figure 1 is a plan view of a parcel wrapper embodying my invention shown in extended form,

Fig. 2, a detail section taken on line 2—2 25 of Fig. 1,

Fig. 3, a longitudinal section of the wrapper showing it in closed position,

Fig. 4, an enlarged detail section taken on line 4—4 of Fig. 3, and

Fig. 5, a plan view of an adhesive closing flap which may be employed in conjunction with the construction.

The preferred form of construction as 30 illustrated in the drawings, comprises a substantially rectangular sheet 6 of comparatively heavy paper and having a pocket 7 secured to the inner side thereof adjacent one end, said pocket being provided with bellows sides 8 as indicated. A securing flap 9 is secured to the other end of sheet 6 and is provided with an adhesive surface 10 for securing the sheet in rolled tubular form. As shown in Fig. 2 the flap 9 is preferably 35 secured to the inner side of sheet 6 then folded over the end and outer side thereof and refolded on itself to make a secure reinforced connection at this point. End closing flaps 11, 12 and 13 are arranged in each side of sheet 6 the line of juncture with said 40 sheet being reinforced by a strip of cloth 14 being pasted thereover. The central flap 12 in each set is made outwardly divergent in form and is provided with a central crease 15 to facilitate insertion in the end of the tube formed by rolling sheet 6 about pocket 55 7 as indicated in Figs. 3 and 4, said flap 12

expanding after insertion to interlock in the tube.

In use an article desired to be shipped or otherwise transported is inserted in pocket 60 7 and the sheet 6 rolled or wrapped about said pocket as indicated in Fig. 4, the flap 9 being secured by adhesive surface 10 as shown. The flaps 11, 12 and 13 are inserted 65 within the ends of the tube thus formed either during the rolling process or after the rolling has been completed to close the ends of the tube thus formed and further insure against loss of articles from the pocket 7. Owing to the outwardly divergent form of 70 flaps 12, they tend to expand in the tube and thus interlock therewith to hold the ends of the tube closed and sealed.

In Fig. 5 I have illustrated a form of adhesive securing flap which consists of a base 75 or a body portion 16 provided with adhesive upon one side to extend the full width of sheet 6, said base being provided with a narrower tongue or extension 17 which is made narrow enough for insertion in an ordinary 80 typewriter for writing an address thereon. Tongue 17 is also provided with an adhesive surface 18 for securing the wrapping in closed condition. When this form of sealing flap is employed the address is first written 85 on the tongue 17 whereupon portion 17 is moistened and applied to the end of sheet 6, flap 9 being omitted in this instance. Then the package is completed as before and is secured in closed position by moistening the 90 surface 18 and securing the same to the side of the tube thus formed.

While I have illustrated and described the preferred form of construction for carrying my invention into effect, this is capable of 95 variation and modification without departing from the spirit of the invention. I therefore, do not wish to be limited to the precise details of construction set forth, but desire to avail myself of such variations and 100 modifications as come within the scope of the appended claims.

Having described my invention what I 105 claim as new and desire to secure by Letters Patent is:

1. A parcel wrapper comprising a flexible sheet adapted to be rolled into a tube; three adjoining flaps on each side of said sheet adapted to be inserted in the ends of said tube, the central flap on each side of said 110 sheet being outwardly divergent in form and adapted to expand in and interlock with said

tubes; and an adhesive flap on said sheet, substantially as described.

2. A parcel wrapper comprising a flexible sheet adapted to be rolled into a tube; flaps on each side of said sheet adapted to be inserted in the ends of said tube, one flap on each side of said sheet being outwardly divergent in form and adapted to expand in and interlock with said tubes; and an adhesive flap on said sheet, substantially as described.

3. A parcel wrapper comprising a flexible sheet; a pocket arranged on the inner side of said sheet at one end, said sheet being

adapted to be rolled about said pocket into a tube; three adjoining flaps on each side of said sheet adapted to be inserted in the ends of said tube, the central of each set of flaps being outwardly divergent in form; and an adhesive flap at the other end of said sheet, substantially as described.

In testimony whereof I have signed my name to this specification in the presence of two subscribing witnesses.

GASTON J. GORY.
